PROCESS OF MAKING MOCCASIN TYPE SHOES
 Allan MacPherson, 14 Park Road, Brockton, Mass.
 Filed June 14, 1963, Ser. No. 287,857
 4 Claims. (Cl. 12—142)

This invention comprises a new and improved process of making a welted shoe of the moccasin type. Many attempts have been made to provide such shoes with a standard Goodyear welt by which all the advantages of such construction may be realized; as for example, by stitching a welt to the moccasin blank in flat condition or by providing an insole to which the welt may be attached. These attempts have not been entirely satisfactory for one reason or another. The operation of lasting a moccasin blank having an already attached welt makes the lasting operation difficult, while the provision of an insole detracts from the desired flexibility of the shoe.

The present invention rests upon my discovery of a process by which a welt strip may be stitched directly and in accurately gauged position to the sole portion of a lasted moccasin. This new process may be briefly characterized by the employment of a preformed welt gauging pattern which is temporarily attached to the bottom of the lasted moccasin and serves to determine positively and accurately the position of the welt strip as it is presented to the moccasin by the welt guide of a Littleway lock stitch machine or other suitable sewing machine. In addition to its gauging function such a pattern prevents collapse of the upper when the last is withdrawn in preparation for the stitching operation.

For the purpose of carrying out the process of my invention the shoe manufacturer always has available a paper or cardboard insole pattern for the contemplated shoe. From this pattern it is an easy step to form a templet which may be about one-half inch smaller in dimensions than the insole pattern and may if desired be cut somewhat closer in the shank. From this templet is prepared a welt gauging pattern and this may be of insole pattern board or other stiff sheet material. The welt gauge pattern thus provided is now spotted on the bottom of the lasted moccasin and thereby defines upon the bottom a marginal welt receiving area. Now, upon withdrawal of the last, the welt strip may be presented accurately against the edge of the welt gauge pattern and secured by a line of lock stitching passing through the welt strip and the underlying bottom of the moccasin. Subsequently an outsole may be stitched to the welt and a moccasin type shoe thus provided which has all the advantages of a standard Goodyear welt shoe.

These and other features of the invention will be best understood and appreciated from the following description of a preferred manner of carrying out my novel process as illustrated in the accompanying drawings in which—

FIG. 1 is a diagram of the insole pattern and templet for the welt gauging pattern,

FIG. 2 is a plan view depicting the welt sewing step,

FIG. 3 is a sectional view on the line 3—3 of FIG. 2 on an enlarged scale,

FIG. 4 is a view in elevation depicting the step of spotting the welt gauging pattern on the lasted shoe bottom, and

FIG. 5 is a fragmentary view suggesting the outsole stitching step.

The shoe manufacturer has as part of his equipment for the contemplated shoe a paper insole pattern 10 such as that indicated in dot and dash lines in FIG. 1. Although no insole is employed in the present process the pattern 10 is useful in preparing a paper templet 11 for the welt gauging pattern 12. This may be formed of insole pattern board, cardboard, or the like, and coincides in contour substantially with the templet 11 except that it may be

2

cut somewhat closer in the shank. It may be conveniently formed on the well known "Planet Sole Rounder."

Meantime, in the course of the process, the full moccasin blank 14 has been lasted in the usual manner upon a last 13 with its sole portion 15 lying flat upon the last bottom and supported thereby. The shoe bottom is thus presented in the most favorable condition to have the welt gauging pattern 12 spotted thereon and temporarily secured thereto as suggested in FIG. 4. In this step a one-way cement, as latex, is applied in the areas 16 and 17 indicated by dotted lines in FIG. 2. The spotting and securing of the pattern 12 to the shoe bottom requires skill and judgment on the part of the operator but no more than is expected as a matter of course in the manufacture of "Compo" cement-lasting shoes.

The last 13 is now withdrawn from the shoe leaving the stiff pattern 12 attached to the shoe bottom as shown in FIGS. 2 and 3, and providing by its marginal edge a positive gauge line setting off a flat marginal welt-receiving area in the bottom 15 of the moccasin. The pattern also imparts a temporary stiffness to the bottom 15 which facilitates handling of the shoe in the welt sewing step, now to be described.

This may be carried out with the assistance of any straight-needle sewing machine having a welt guide. The welt guide of the Littleway machine is shown in FIGS. 2 and 3. It comprises a bracket 20 by which it is bolted in place in the machine head. The bracket 20 merges downwardly into a gauge arm 21 having a flat outer gauging face adapted to run against the upright shoulder of the welt gauging pattern 12.

The welt guide has also an outwardly extending lateral arm 22 carrying beneath it an adjustable guide block 19 and a roller edge guide 23 mounted upon a stud 24. The welt passage is formed between the outer face of the gauge arm 21 and the inner face of the guide block 19. The welt 28 is partially overlaid by a portion of the lateral arm 22. Both this and the inner face of the edge gauge 21 are beveled to form a slot 25 for the passage of the needle 26. As it passes through the welt passage the welt 28 is thus positively located a short predetermined distance from the edge of the pattern 12 and directly in line with the path of the needle 26. It is secured permanently to the bottom portion 15 of the moccasin by a line 29 of lock stitches.

It will be apparent that the welt 28 has thus been located and secured in an accurate, positively gauged manner while the work in the hands of the operator is supported by the pattern 12 which is laterally or transversely stiff. This temporary stiffening pattern is now stripped off the bottom of the shoe leaving the shoe bottom in condition to receive a filler 32 of any kind between the inner margins of the welt 29 and to have an outsole 30 stitched to the welt by stitch line 31 in accordance with standard Goodyear welt procedure.

Having thus disclosed by invention and described in detail an illustrative embodiment thereof, I claim as new and desire to secure by Letters Patent:

1. The process of making moccasin type shoes, comprising the steps of lasting a moccasin blank, temporarily attaching to the sole portion of the lasted blank a stiff sole-shaped pattern thereby setting off a marginal welt area, then removing the last, gauging a welt strip against the edge of said pattern, attaching the welt while thus gauged to the unsupported sole portion of the moccasin, removing the sole-shaped pattern, and stitching an outsole to the welt.

2. The process of making moccasin type shoes, comprising the steps of making templet of size reduced from the insole pattern of the contemplated shoe, preparing from the templet a welt-gauging pattern coinciding in contour with the templet, temporarily securing the welt-gauging

pattern to the sole portion of a lasted moccasin, removing the last, sewing the welt to the sole portion of the moccasin while gauged against the welt-gauging pattern, and stitching an outsole to the welt.

3. In a process of making moccasin type shoes, the steps of temporarily securing to the sole portion of a lasted moccasin a stiff sole-shaped pattern thereby setting off a marginal welt area therein, removing the last, and stitching a welt strip to the sole portion of the moccasin while progressively gauging the welt against the pattern which is still secured to the sole portion of the moccasin. 10

4. In a process of making moccasin type shoes, the steps of temporarily cementing to the bottom of a lasted moccasin a stiff sole-shaped pattern thereby setting off a

marginal welt area of about three-fourths of an inch and stiffening the enclosed area of the moccasin bottom, pulling the last, and then stitching a welt strip to the moccasin bottom while the latter is supported by the cemented pattern and while the welt strip is gauged against the edge of the pattern.
